MACHINE FOR MAKING BLADE ENVELOPES

Edward A. Stalker and Daniel J. Clarke, Bay City, Mich., assignors to The Stalker Corporation, a corporation of Michigan

Filed Jan. 3, 1957, Ser. No. 632,351
7 Claims. (Cl. 153—48)

This invention relates to the making of hollow blades for compressors, turbines and the like and its object is to provide a machine for stretch forming the envelopes or shells of such blades.

Other objects and advantages will appear from the specification, accompanying drawings and appended claims.

In the drawings which disclose a preferred embodiment of the invention, in which—

FIG. 1 is a side elevation of the machine for forming the envelopes or shells of blades according to this invention;

FIG. 2 is a top plan view of the machine of FIG. 1;

FIG. 3 is a horizontal section on line 3—3 of FIG. 5;

FIG. 4 is a plan view of a blade blank with the cleats or stops secured to the side edges thereof;

FIG. 5 is a side elevation of the machine partly in section;

FIG. 6 is a perspective view of the blank as it comes from the press;

FIG. 7 is a perspective view of the male die; and

FIG. 8 is an end elevational view of the blank after the side edges have been trimmed off.

The machine is indicated generally as 10 in FIG. 1. It comprises a male die 12 and a female die assembly having contoured wall surfaces on die members 14 and 15 supported in operable relation with a recess 20 therebetween so that the male die can be advanced against a blade blank 16 positioned on the ends of the dies and lying across the recess 20.

As shown in FIGS. 1, 2 and 5 the male die is advanced fully without a blade blank in the machine. In FIG. 3 the male die is in its most advanced position with a blade blank in place and has stretched the blank so that it has taken on the proper shape from the dies. To accomplish the stretching the blank is restrained by cleats 24 preferably spot-welded to the blank forming positive stops. As the male die advances the cleats are drawn inward until they are seated against the abutments 26 and 28. This seating occurs before the male die reaches the end of its stroke. Further movement of the male die causes stretching of the metal of the blank as it is formed over the contoured walls of the female dies.

In FIG. 5 the frame of the press is indicated as 30 including upper horizontal arms 32 integral with the lower horizontal members 34. These support the vertical end member 36 fixed to the upper arms 32 and the lower members 34, respectively.

The base plate 40 is fixed to the end member 36 and the female die members 14 and 15 are fixed to it by studs 41. The base plate 40 supports four horizontal guide posts 44 which pass through bearings in the die plate 46 and guide the latter. The male die is fixed to the die plate and derives its stroke from the movement of the plate.

The male die and die plate are reciprocated by a piston in cylinder 50. Its piston rod 52 is suitably fixed to the drive rod 54 and the forward end of rod 54 is fastened to the stud 55 of male die 12 by means of pin 56 with die plate 46 therebetween. The reciprocating motion of the rod is controlled by admitting fluid pressure alternately to opposite ends of the cylinder through pipes 60 and 62 and valve 64 controlled by handle 66. The

2

pipes 68 and 70 conduct fluid to and from a source of fluid under pressure.

It has been found desirable to allow relatively free movement of the blade blank on its support in the initial portion of the forming operation but to firmly secure the blank along its side edges in the latter portion of the operation, in order to assure the desired stretch forming thereof over the die faces. Accordingly means is provided for engaging the lateral edges of the blank after the male die has operated over the initial portion of its stroke and for positively holding the same against movement for the remainder of the stroke. For this purpose the drive rod 54 is formed with cam blocks 100, 102 on opposite sides thereof and such cam blocks engage and actuate a pair of rollers 82, 84, mounted on opposite sides of the rod in cam follower members 86, 88, pivoted at 90, 92 respectively in the frame 94. The cam follower members are connected to links 96, 98 by pivots 97 and to brackets 99 fastened to the body of abutment block 80 by pivots 97a. The latter has a central aperture to receive the male die 12, allowing the same to operate therethrough without interference. On its working face the abutment block carries hardened replaceable inserts 110 which are formed with right-angle notches 26, 28 adapted to engage the stops 24 of the blank. As will be clear from FIG. 4, such stops extend preferably throughout the length of the blank and along both sides edges thereof, the notches on the lower face of inserts 110 being similarly shaped so that a positive engagement 30 along both lateral edges of the blank is assured.

In order to provide for return movement of the abutment block 80 after the working stroke, the die plate 46 has notches on its opposite sides through which the links 96 and 98 pass freely, and outwardly thereof the plate carries straps 115 which are adapted to engage with pins 116 fixed in the respective links in the final withdrawing movement of the drive rod.

In operation, a flat piece of sheet metal 16 has the cleats or stops 24 spot-welded thereto and is placed in position on the end of the female die extending across recess 20, any suitable means such as vertical stops 25 being used to retain the same in position. The hydraulic motor is actuated to advance the male die toward and into engagement with the blank, the initial travel being allowed to take place with the sides of the blank substantially free of restraining force, and thus allowing the sheet to be forced into the female die recess. As the stroke proceeds, the rise on cam blocks 100, 102 will actuate cams 86, 88 and thereby advance abutment block 80 into the position shown in FIG. 3 such that the notches 26, 28 on insert 110 will intercept and positively stop further lateral travel of the sides of the blank. Since this occurs before the end of the stroke of the male die, the remaining travel of the latter results in stretch forming of the metal over the respective die surfaces. The final travel of the male die is controlled by the provision of stops 120 on abutment block 80 upon which lateral projections of the male die bear to thus accurately fix the limit of its forward travel.

While the sheet is being stretched the cleats secure the edges without significant axial force being applied and hence the links 96, 98 and associated cam mechanism can be of relatively lightweight construction. Further the force of the hydraulic fluid in the cylinder is not dissipated by the holding operation and since the cleats bear in opposite directions on the abutment block the forces developed therein are balanced and confined to the block itself without being transmitted to the remainder of the press. The abutment block is preferably a unitary element and such balanced force condition further results in reducing the stresses required to be borne by the remaining press structure.

Upon retraction, the male die is withdrawn and in the

A latter portion of its return movement the straps 115 engage pins 116, thereby releasing the engagement between abutment block 80 and the cleats 24 so that the formed blank can then be removed from the press. The abutment block and its holding function are therefore caused to take place in correlated relation with but in a different time cycle from the actual movement of the male die itself and with a shorter stroke, sufficient to clear the stops on the blank.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A machine for stretch forming blades for compressors, turbines and the like from a flat sheet metal blank provided with cleats along the lateral edges thereof which comprises female die members having a recess therebetween with walls of predetermined contour and adapted to receive the blank at the end thereof extending across said recess, a male die shaped to engage said blank and to force the same into said recess for performing the desired blade shape over said contoured die walls, an abutment block movable with said die toward and away from said blank and having means thereon adapted to engage said cleats; means for advancing said male die and abutment block on a working stroke, linkage means controlling the movement of said abutment block means relative to said male die into the path of said cleats leaving said blank substantially free of restraining force during an initial portion of the travel of said male die and said block and for effecting positive stopping of said lateral edges of the blank by said block in the latter portion of the travel of said die to effect a final stretch forming of said blank, and means provided on said linkage means for retracting said abutment block following said working stroke of said linkage control means.

2. A machine for stretch forming blades for compressors, turbines and the like from a flat sheet metal blank which comprises female die members having a recess therebetween with walls of predetermined contour and adapted to receive the blank at the end thereof and extending across said recess, a male die shaped to engage said blank and to force the same into said recess for performing the desired blade shape over said contoured die walls with the lateral edges of the blank supported freely, an abutment block movable with said die toward and away from said blank and having opposite retaining means thereon adapted to engage said blank along opposite lateral edges thereof, power means for advancing said male die and abutment block on a working stroke, operating means for advancing said abutment block on a time cycle different from that of said die advancing means to establish engagement of said block with said lateral edges of said blank at a predetermined point after the male die has entered said die members with resultant final stretch forming of the blank over said contoured wall surfaces, and means provided on said power advancing means for retracting said abutment block following said movement of said male die away from said blank.

3. A machine for stretch forming blades for compressors, turbines and the like from a flat sheet metal blank having stops on the opposite lateral edges thereof which comprises female die members having a recess therebetween with walls of predetermined contour and adapted to receive the blank at the end thereof extending across said recess, said stops extending outwardly of the major surface of said blank, a male die shaped to engage said blank and to force the same into said recess for performing the desired blade shape over said contoured die walls with the lateral edges of the blank supported freely, an abutment block movable with said die toward and away from said blank and having retaining means thereon

adapted to engage said opposite stops on said blank, means for advancing said male die and abutment block on a working stroke, operating means controlling the movement of said abutment block into engagement with said blank following engagement of said male die with said blank leaving said blank substantially free of restraining force during an initial portion of the travel of said male die and for effecting engagement between said block and said stops in the latter portion of the travel of said die to effect final stretch forming of said blank with the stretching forces on said retaining means being carried by said block in directions transverse to the direction of movement of said abutment block with opposition of one said stretching force to the other, and means provided on said advancing means for retracting said abutment block following said working stroke of said advancing means.

4. A machine for stretch forming blades for compressors, turbines and the like from a flat sheet metal blank having stops on the opposite lateral edges thereof which comprises female die members having a recess therebetween with walls of predetermined contour and adapted to receive the blank at the end thereof and extending across said recess, a male die shaped to engage said blank and movable on a working stroke to force the same into said recess for performing the desired blade shape over said contoured die walls and movable away from said blank for disengagement therefrom, an abutment block movable with said die toward and away from said blank and having means thereon adapted to engage said stops on said blank, power means for advancing said male die and abutment block on a working stroke, operating means for advancing said abutment block on a working stroke on a time cycle different from that of said die advancing means to establish engagement with said blank stops at a predetermined point in the metal forming portion of the working stroke of said male die with resultant final stretch forming of the blank over said contoured wall surfaces, and means provided on said power advancing means for retracting said abutment block following said movement of said male die away from said blank.

5. A machine for stretch forming blades for compressors, turbines and the like from a flat sheet metal blank having stops along the opposite lateral edges thereof which comprises female die members having a recess therebetween with walls of predetermined contour and adapted to receive the blank at the end thereof extending across said recess, said stops extending outwardly of the major surface of said blank, a male die shaped to engage said blank and movable on a working stroke to force the same into said recess for performing the desired blade shape over said contoured die walls, an abutment block movable with said die toward and away from said blank and having means thereon adapted to engage the stops on said blank, power means for advancing said male die and abutment block on a working stroke, operating means arranged in balanced relation for advancing said abutment block after a predetermined part of the metal forming stroke of said male die to a position to intercept said stops in the final portion of the travel of said male die, and means provided on said power advancing means for retracting said abutment block following said working stroke of said operating means.

6. A machine for stretch forming blades for compressors, turbines and the like from a flat sheet metal blank having stops along the opposite lateral edges thereof which comprises female die members having a recess therebetween with walls of predetermined contour and adapted to receive the blank at the end thereof extending across said recess, said stops extending outwardly of the major surface of said blank, a male die shaped to engage said blank and movable on a working stroke to force the same into said recess for performing the desired blade shape over said contoured die walls, an abutment block movable with said die toward and away from said

blank and having means thereon adapted to engage the stops on said blank, power means for advancing said male die and abutment block on a metal working stroke including a drive rod, means having a connection to said drive rod operable after said male die has engaged and preformed said blank to effect advance of said abutment block into a position loosely engaging said blank and a position to intercept said stops thereon at a predetermined point in advance of the end of said working stroke, and additional means operatively connected with said abutment block for retracting the same following said working stroke thereof.

7. A machine for stretch forming blades for compressors, turbines and the like from a flat sheet metal blank having stops along the opposite lateral edges thereof which comprises female die members having a recess therebetween with walls of predetermined contour and adapted to receive the blank at the end thereof extending across said recess, a male die shaped to engage said blank and movable on a working stroke to force the same into said recess for preforming the desired blade shape over said contoured die walls, an abutment block movable with said die toward and away from said blank and having opposite retaining means thereon adapted to engage the stops on said blank, power means for advancing said male die and

15

20

25

abutment block on a metal working stroke including a drive rod, means having a connection to said drive rod operable to effect advance of said abutment block into a position loosely engaging said blank and a position to intercept said stops thereon at a predetermined point in advance of the end of said metal working stroke of said male die insuring that said blank is free of restraining forces at said lateral edges while it is being drawn into said recess by said male die over a predetermined portion of its stroke and that said edges are restrained over the remaining portion of said stroke of said male die to effect stretch forming of said blank on said dies, and means for retracting said block on the return stroke of said drive rod to release said blank.
